Primary Examiner—B. J. Bullock*Attorney, Agent, or Firm*—Gilberto M. Villacorta, Pepper Hamilton LLP[57] CLAIM

The ornamental design for a garment clip, as shown and described.

DESCRIPTION

FIG. 1 is a perspective view of a garment clip, showing my new design;

FIG. 2 is a top view thereof;

FIG. 3 is a bottom view thereof;

FIG. 4 is an end view thereof;

FIG. 5 is a side view thereof; and,

FIG. 6 is a reduced perspective view of the design in its environment which is shown in broken lines for illustrative purposes only and which form no part of the claimed design.
